UNITED STATES PATENT OFFICE.

AXEL BERGSTROM, OF HOQUIAM, AND ALBERT E. GREENE, OF SEATTLE, WASHINGTON,
ASSIGNORS TO GREENE PROCESS METAL COMPANY, OF ST. LOUIS, MISSOURI, A
CORPORATION.

LADLE HANGER.

Application filed June 30, 1921. Serial No. 481,677.

To all whom it may concern:

Be it known that we, AXEL BERGSTROM, a citizen of the United States, residing at Hoquiam, in the county of Grays Harbor and State of Washington, and ALBERT E. GREENE, a citizen of the United States, residing at Seattle, in the county of King and State of Washington, have invented certain new and useful Improvements in Ladle Hangers, of which the following is a specification.

This invention relates to ladle hangers, and is an attachment for tilting furnaces designed to hold ladles and is more particularly intended for use of electric furnaces.

The object of our invention is to fill ladles with molten metal while the ladle hangs in a suitable hanger attached to the furnace.

20 The invention consists in one modification of a pair of frames which may be attached to the furnace shell or spout and adapted to support a ladle shank whereby the ladle may be held in position with relation to the spout of the furnace so that on tilting the furnace over the metal will enter the ladle and on filling of the ladle the furnace may be tipped back until the metal stream stops and then the ladle may be taken away for pouring the molten metal.

In another modification hangers are hung on supporting brackets so as to always hang in a vertical position when the furnace is tilted.

35 Heretofore it has been customary for two men to hold the ladle in a shank in front of the furnace while the metal is poured into the ladle. This practise results in spilling the metal and is dangerous on account of the sparks and particles of molten metal which may spatter and burn the workmen. The purpose of this invention is to provide a means of holding the ladle in position under the spout of the furnace in such 45 manner that the stream of metal will enter the ladle irrespective of the position of the furnace whether it be tilted over or in the normal position.

One feature of this invention consists in 50 providing suitable slots in the fixed frame which supports the shanks of the ladle whereby the ladle may be held in front of the spout.

In one modification this invention pro-

vides special shaped slots in which the ladle 55 shanks rest to prevent the ladle from tipping over and spilling the metal.

In another modification this invention provides means of varying the position of the hanging members which hold the ladle 60 shank, whereby ladles of varying diameters may be used in the same hanger and whereby the position of the ladle with respect to the end of the spout may be adjusted in accordance with the position which the metal 65 stream takes on leaving the spout.

Another feature of our invention relates to construction of the hanging members which are attached to the furnace shell or to brackets fixedly connected thereto and 70 another feature relates to notches provided for varying the position of either the ladle shank on the fixed members or for varying the position of a slotted hanging member which latter member may hold the ladle 75 shank.

Another feature of our invention is the construction of the hanging members.

These and other features of the invention will be better understood with reference to 80 the drawings.

Fig. 1 shows a view in elevation of a furnace and ladle hanger from the front of the furnace.

Fig. 2 shows another view of this same 85 furnace, spout, ladle hanger and ladle from the side of the furnace.

Fig. 3 shows an end view of a furnace and of another modification of ladle hanger.

Fig. 4 shows a view of the ladle hanger 90 and furnace spout of Fig. 3 from in front of the furnace spout.

Fig. 5 shows one view of the top of the hanging members.

Fig. 6 shows another side view of the 95 member of Fig. 5.

With reference to these drawings, the invention will be described in further detail.

The ladle hanger shown in Fig. 1 is shown as attached to a furnace mounted on trunnions.

Referring to Figs. 1 and 2, 1 is the shell of the furnace which may be rotated on the trunnions 2 in the bearings 3. The spout of this furnace is shown at 7. The 105 modification of ladle hanger shown in Figs. 1 and 2 consists of two frame members 4 and 4 attached to the furnace shell by

means of bolts 5. In these figures these frame members 4, 4 consist of structural steel angle irons. Attached to each of these angle irons 4, 4 is a notched member 6 supported by any suitable construction such as the piece 15 which holds the members 6 in outward relation from the furnace shell. Notches 8, 9 and 10 are provided in the members 6 and are designed to hold the shanks 11 of the ladle. The ladle 12 is shown in position underneath the spout ready to take the stream of molten metal when the furnace is tilted over. In this modification of ladle hanger the ladle may be held upright by the workman keeping his hand on the end of the ladle shank to keep the ladle in vertical position while the furnace is tipped over. The notches 8, 9 and 10 are made round whereby the ladle may be tilted by turning the shank. In another modification of this invention described further on a special shaped slot is provided in a separate member whereby the ladle is prevented from tipping over while held in the slot. On tipping the furnace shown in Figs. 1 and 2, the stream of metal enters the ladle and when the ladle is sufficiently full the furnace is tipped back and the pouring discontinued. The ladle may then be taken away for pouring its contents into suitable molds.

Referring to Figs. 3 and 4 a furnace of the rolling cylinder type is shown. Attached to the spout of this furnace are two notched members 23. These members are attached to the spout 22 of the furnace 21 by means of bolts whereby they may be quickly removed in case it is desired to have them out of the way when a crane ladle or other type of ladle is used. However, these extensions can be cast as a part of the ladle spout if desired. The side view of these members 23 is shown in Fig. 3. Fig. 4 shows these members 23 from the front where it is seen that the parts of the members 23 which extend outwardly from the furnace spout are also provided with an extension whereby the notched portion of these members are at a greater distance apart than the width of the spout at the place where these members are bolted or attached to the spout. This construction is intended to keep the slotted members 26 which hang in the notches of the members 23 far enough away from the ladle so that in case slag or metal spills over it will not enter the slots of the members 26 and will therefore not interfere with the holding or removing of the ladle shank from the slotted member. The slotted members 26 consist of suitable pieces of steel or other sufficiently strong metal to support the weight of the filled ladle. The slots 27, 30 and 31 are provided so that the ladle may be hung at whatever elevation is desired and so that ladles of different sizes may be conveniently used. Any suitable number of

notches in the members 23 and slots in the members 26 may be provided. I prefer to make the members 23 and 26 of cast steel for the purpose of ample strength. A piece of iron or steel rod bent to suitable shape to go over the member 23 and rest in the notches thereof may be cast into the member 26 so as to form a loop or link which serves to hold the slotted member 26 in the notched member 23.

75

The dotted lines 32 in Fig. 3 and the numerals 29^A, 22^A and 26^A show the position of the ladle and spout and ladle hanger, the metal stream 32 entering the ladle when the furnace is rolled over for the purpose of pouring.

The slots in the members 26 are shown as elongated and Fig. 3 shows the ladle shank in section taken through the center of one of the slots of the members 26 and the shank of the ladle is flattened to prevent the ladle from tipping over.

When pouring in hand ladles in what is ordinarily known as a one man shank the shank may be held on one side of the ladle hanger, that is in one of the slotted members 6 or 26.

This invention results in very material improvement in the pouring of metals especially steel and brass for it is possible to fill the ladle without danger to the workmen holding the shanks and the pouring may be completed without the workman touching the ladle shank where this is desired. This invention therefore makes it possible for a furnace to be operated by a very much smaller crew than has usually been required heretofore. The furnace man can tilt the furnace and fill the ladle and then tilt the furnace back and then assist his helper in pouring the ladle full of metal. It is also found that a very great saving of metal results because the operators are not afraid from the spattering of the stream of metal.

110

What we claim is:—

1. A ladle hanger for a tilting furnace comprising a frame attached to the furnace and provided with a slotted member adapted to support the shank of a ladle whereby the ladle may be supported in a position to catch the metal stream from the furnace spout as the furnace tips over.

115

2. A ladle hanger comprising two notched members attached to the spout of the furnace and extending outwardly from the furnace shell and provided with notches at various distances from the end of the furnace spout adapted to support a hanging member in said notches; and said hanging member having suitable slots for holding the shanks of a ladle shank in position under the spout of the furnace.

120

3. A ladle hanger for a tilting furnace comprising outwardly extending shank comprising

125

130

- holding members one on each side of the furnace spout said members arranged to maintain a ladle beneath said spout in a position to catch the metal stream during 5 the movement of the furnace in tilting.
4. In combination, a tilting furnace, a pouring outlet therefrom, ladle supporting members projecting from said furnace in proximity to said pouring outlet, and shank 10 retaining means on said members.
5. In combination, a tilting furnace, a
- pouring outlet therefrom, ladle supporting members projecting from said furnace in proximity to said pouring outlet, detachable hangers adjustably retained by said 15 members, and means on said hangers to hold the shanks of a ladle.

In witness whereof we hereunto subscribe our names, this 22 day of June, 1921.

AXEL BERGSTROM.
ALBERT E. GREENE.
